(57) **CLAIM**

The ornamental design for a wearable interface for intelligent health promotion service system, as shown and described.

DESCRIPTION

FIG. 1 is a front perspective view of a wearable interface for an intelligent health promotion service system showing my design.

FIG. 2 is a rear perspective thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a top plan view thereof in an unwrapped configuration; and,

FIG. 10 is an exploded view thereof.

1 Claim, 10 Drawing Sheets
